UNITED STATES PATENT OFFICE.

LEO G. HAASE, OF PASADENA, CALIFORNIA.

DESIGN FOR A DOUBLE BENCH.

57,644.

Specification for Design.

Patented Apr. 26, 1921.

Application filed October 13, 1919. Serial No. 330,492. Term of patent 14 years.

To all whom it may concern:

Be it known that I, LEO G. HAASE, a citizen of the United States, residing at Pasadena, in the county of Los Angeles and State of California, have invented a new, original, and ornamental Design for Double Benches, of which the following is a specification, reference being had to the accompanying drawing, forming part thereof.

Figure 1 is an end view of my ornamental double bench.

Fig. 2 is a perspective view of the same.

I claim:

The ornamental design for a double bench as shown.

LEO G. HAASE.
